UNITED STATES PATENT OFFICE

RAYMOND L. HARRISON, OF ALBUQUERQUE, NEW MEXICO

EARTH MOVING DEVICE

Application filed August 28, 1930. Serial No. 478,432.

My invention relates generally to an earth working apparatus, and more particularly to apparatus of the scraper type adapted to be drawn across the surface of the ground.

It is one of the primary objects of my invention to provide a simple and improved earth working or moving device which may be conveniently and automatically controlled by an operator remotely positioned from the earth receiving device or scraper proper.

More specifically my invention contemplates the provision of a very simple and improved hydraulic mechanism for controlling the tilting of a scraper or earth receiving bowl without requiring the use of a hydraulic pump.

A still further and more specific object of my invention is to provide a substantially closed hydraulic circuit for controlling the shifting of an earth receiving bowl or scraper, said circuit functioning in response to the force exerted by the mechanism such as a tractor, which is employed to draw the scraper over the surface of the ground.

These and numerous other objects and advantages will be more apparent from the following detailed description when considered in connection with the accompanying drawings, wherein:

Figure 1 is a side elevational view of an earth working or moving device which is representative of one embodiment of my invention;

Figure 2 is a similar side elevational view disclosing the scraper or fresno in a shifted position; and

Figure 3 is a plan view of the mechanism as shown in Figure 2.

Referring now to the drawings more in detail, wherein like numerals have been employed to designate similar parts throughout the various figures, it will be observed that one embodiment of my invention includes a draft frame 10, which is pivotally coupled at its rear extremity on opposite sides of a scraper or fresno bowl 14, through the agency of a suitable shaft 16.

Positioned upon the peripheral surface of the bowl 14 is a lug 18 which is adapted to engage a pivoted latch member 20. This latch

member 20 is pivoted at 22 upon one extremity of a horizontal shiftable actuator bar 24, which forms a part of an actuator mechanism designated generally by the numeral 26. The latch member 24 is secured against counter-clockwise movement as viewed in Figures 1 and 2, when a cooperating section of a trip lever 28 is positioned as shown in said figures. The operation of this trip lever 28 is manually controlled by an operator positioned in the seat 30 of a tractor (not shown) through the agency of a suitable cord 32. The actuator bar 24 is provided with an arcuate slot 34 which receives a pin 36 carried at the upper end of a vertical frame member 38.

This arcuate slot 34 serves when the actuator bar 24 is horizontally shifted to guide the latch member 20 in an arcuate path in conformity with the arcuate travel of the lug 18. The provision of this arcuate slot in the latch member 24 does not form a part of the present invention except in so far as it enters into the general combination thereof, and the specific construction of this arcuately formed portion of the actuating member is covered in my co-pending application, Serial Number 449,911, filed May 5, 1930. It will suffice, however, to state that as the actuator member is shifted from the forward position shown in Figure 1 to the rearward position shown in Figure 2, the latch member 20 will move in the same arcuate path as the lug 18, thereby maintaining proper engagement with said lug. A coil spring 40 is interposed between the latch member 20 and the pin 36 and serves to yieldingly urge said latch member in a clockwise direction.

The forward extremity to the right, Figures 1 and 2, of the actuator member 24 is pivotally connected to the upper end of an actuating lever 42, which is pivotally mounted at its intermediate portion upon a pin 44, which is adapted to extend through one of a plurality of apertures 46 provided in an upright frame or support 48. The lower extremity of the actuating lever 42 is pivotally connected with one end of a shifter rod 50.

This shifter rod 50 is formed in two sec-

tions, said sections being connected by a coupler 52. This coupler 52 serves to vary the length of the rod 50. This rod 50 passes through a cylinder 54 and is connected at its outer extremity to the coupling 56 of a tractor or other suitable tractive mechanism (not shown). A suitable piston 58 is carried by the rod 50 within the cylinder 54. One extremity of the cylinder 54 communicates with one extremity of a tank 60 through the agency of a connecting pipe 62, while the other extremity of the cylinder 54 is adapted to be connected and disconnected with respect to the tank 60 through the agency of a suitable valve 64. This valve is operated in any suitable manner as by means of a suitable connector rod or member 66 which extends to a convenient location in the tractive mechanism, as, for example, to a point adjacent to the driver's seat 30.

From the foregoing description it will be apparent that if the bowl 14 occupies the position shown in Figure 1 with its cutting edge 14^a positioned below the surface of the ground, and a pulling force is exerted on the draft frame 10 to the right, earth will be taken into said bowl. After a sufficient quantity of earth has been taken into the bowl, and it is desired to tilt said bowl rearwardly to the position shown in Figure 2, it is only necessary to open the valve 64. This will permit free movement of the piston 58 to the right within its cylinder 54, and this movement will cause the actuator lever 42 to be swung in a counter-clockwise direction, thereby causing the latch member 20 to be urged rearwardly against the lug 18. When the position of the bowl 14 as shown in Figure 2 is reached, the valve may be closed and the tractor drawn across the surface of the soil without making a cut. The position of the bowl shown in Figure 2 is commonly referred to as a drifting position because the cutting edge of the bowl is not digging into the ground. If it is desired to shift the bowl in a still further rearward counter-clockwise direction, this can be done by again opening the valve 64 and allowing the pull of the tractor to cause the actuator 26 to exert a rearward force upon the lug 18.

When it is desired to return the piston 58 to its extreme left position within the cylinder 54, it is only necessary to stop the tractor, open the valve 64 and allow the force of a heavy duty spring 68 to act upon the actuator lever 42. This spring 68 is interposed between the upper extremity of this lever and the tank 60, and is provided with a turn buckle 70 for adjusting the tension thereof. This spring 68 will cause the actuator member 24 to be urged to the right and when a pulling force is again applied to the mechanism, the bowl 24 will be moved to a shifted position, as for example to the position shown in Figure 1.

In order to obtain variations in the stroke of the actuator lever 42, I employ the series of apertures 46 and companion apertures 46^a in the lever. In this manner I am able to vertically adjust the pivotal point without varying to any substantial degree the vertical shifting of the lever itself.

From the foregoing it will be apparent that when the piston 58 occupies the position shown in Figure 1 and the valve 64 is closed, the fluid within the cylinder 54 will serve as a lock or abutment to prevent relative movement between the draft frame 10 and said piston. In other words, under such conditions, when a pulling force to the right is applied to the rod 50, the fluid body to the right of the piston 58 will prevent relative movement between said piston and the draft frame. On the other hand, when the valve 64 is open, and a similar force is applied to the piston 50, fluid from the cylinder 54 will flow through the valve 64 into the tank 60 and from the tank 60 fluid will be returned to the opposite end of the cylinder 54 through the pipe 62. Thus a closed hydraulic circuit is presented which enables the piston 58 to be locked in any position within the cylinder 54.

It might be said that the mechanism including the shiftable rod 50, the cylinder 54, the piston 58, the tank 60, and the fluid body therein, comprises a hydraulic mechanism which serves as means for coupling the draft frame 10 with any suitable tractive means such as a tractor or other vehicle (not shown). Furthermore, this hydraulic mechanism is coupled with the bowl actuating device, namely, the actuator member 24 and the lever 42, and thus serves to control the tilting of said bowl.

Having thus described my invention, what I claim as new and desire to secure by Letters Patent is:

1. In an earth moving device adapted to be moved across the surface of the ground, a tiltable earth carrying means having a material receiving edge, a draft frame pivotally supporting said earth carrying means, a hydraulic mechanism providing a coupling between said draft frame and means for applying a tractive force to said draft frame, said hydraulic mechanism including a cylinder, a piston shiftable within said cylinder, a fluid body providing a lock between the cylinder and said piston, and actuating mechanism for effecting the tilting of said earth carrying means, said mechanism being operable in response to the shifting of the piston within its cylinder.

2. In an earth moving device adapted to be moved across the surface of the ground, a tiltable earth receiving means; a draft frame for pivotally supporting said earth receiving means, a mechanism for connecting said draft frame with a suitable tractive means, said

mechanism including a cylinder, a piston shiftable within said cylinder, means for connecting said piston with said tractive means, a fluid body within said cylinder, means for 5 conducting fluid from one extremity of said cylinder to the opposite extremity thereof, and means for actuating said earth carrying means, said actuating means being operable in response to the shifting of the piston within 10 its cylinder.

3. In an earth working device adapted to be moved across the surface of the ground, a tiltable earth carrying means having an earth receiving edge, a draft frame, mechanism for 15 connecting said draft frame with a suitable tractive means, said mechanism including a cylinder carried by said frame, a piston in said cylinder, means adapted to connect said piston with said tractive mechanism, means 20 for establishing communication between the opposite extremities of said cylinder, including a valve mechanism, and actuator means for said earth receiving means which is operable in response to said piston.

25 4. In an earth working device adapted to be moved across the surface of the ground, a tiltable earth carrying means having an earth receiving edge, a draft frame, mechanism for connecting said draft frame with a 30 suitable tractive means, said mechanism including a cylinder carried by said frame, a piston in said cylinder, means adapted to connect said piston with said tractive mechanism, means for establishing communication 35 between the opposite extremities of said cylinder, including a valve mechanism, and actuator means for said earth receiving means which is operable in response to said piston, and resilient means for continuously acting 40 in a given direction on said actuator mechanism.

5. In earth working apparatus adapted to be moved across the surface of the ground, a tiltable earth receiving means, draft means 45 for urging said earth receiving means across the surface of the ground, hydraulic mechanism providing a coupling between said draft means and suitable tractive means, and means for actuating said earth receiving means, said 50 actuating means being operable in response to said hydraulic mechanism.

6. In an earth working apparatus adapted to be moved across the surface of the ground, a tiltable earth receiving bowl, a draft frame 55 for urging said bowl across the surface of the ground, hydraulic mechanism providing a coupling between the draft frame and suitable tractive means, said hydraulic mechanism including a piston and piston rod shift- 60 able within a cylinder, and a fluid body for locking said piston against movement within said cylinder, and bowl actuating mechanism operable in response to said hydraulic mechanism.

65 7. In an earth working apparatus adapted

to be moved across the surface of the ground, a tiltable earth receiving bowl, a draft frame therefor, hydraulic mechanism providing a coupling between said frame and a suitable tractive means, an actuator member for engaging said bowl to effect the tilting thereof, and means connecting said actuator member with said hydraulic mechanism, whereby 70 said actuator will be moved in response to said hydraulic mechanism.

8. In an earth working apparatus adapted to be moved across the surface of the ground, a tiltable earth receiving bowl, a draft frame therefor, hydraulic mechanism providing a coupling between the draft frame and suitable tractive means, said mechanism including a piston and a piston rod shiftable within a cylinder, means for directing fluid from one side of said piston to the opposite side thereof, remotely controlled valve mechanism for controlling the flow of fluid between the opposite sides of said piston, and an actuating mechanism for controlling the shifting of said earth receiving bowl, said actuating 85 mechanism being connected with said hydraulic mechanism.

9. In an earth working device adapted to be moved across the surface of the ground, a tiltable earth carrying bowl, a draft frame therefor, hydraulic coupling mechanism for connecting said draft frame with a suitable tractive means, a shiftable bowl actuating mechanism connected with said hydraulic mechanism, said bowl actuating mechanism being shifted in one direction in response to a pulling force applied to said hydraulic mechanism by said tractive means, and resilient means for urging said bowl actuating means in the opposite direction.

10. In an earth working apparatus adapted to be moved across the surface of the ground, a tiltable earth receiving bowl, a draft frame for urging said bowl across the surface of the ground, hydraulic mechanism providing a coupling between the draft frame and suitable tractive means, said hydraulic mechanism including a piston and an extensible piston rod shiftable within a cylinder, and a fluid body for locking said piston against movement within said cylinder, and bowl actuating mechanism operable in response to said hydraulic mechanism.

11. In an earth moving device adapted to be moved across the surface of the ground, a draft frame, tiltable earth carrying means on said frame, actuating means engageable with the earth carrying means for tilting same, and a hydraulic mechanism connected with said actuating means, said hydraulic mechanism being adapted for connection with a tractive means and shiftable in response to the force exerted by such tractive means.

12. In an earth moving device adapted to be moved across the surface of the ground, a

draft frame, tilttable earth carrying means on said frame, actuating means engageable with the earth carrying means for tilting same, and a hydraulic mechanism connected with said actuating means, said hydraulic mechanism, including a cylinder and a piston reciprocable therein, adapted for connection with a tractive means and shiftable in response to the force exerted by such tractive means.

13. In an earth moving device adapted to be moved across the surface of the ground, a draft frame, tilttable earth carrying means on said frame, actuating means engageable with the earth carrying means for tilting same, a hydraulic mechanism connected with said actuating means, said hydraulic mechanism being adapted for connection with a tractive means and shiftable in response to the force exerted by such tractive means, and means for remotely controlling the operative functioning of said hydraulic mechanism.

14. In witness whereof, I have hereunto subscribed my name.
